EDWIN O. KLEMM, OF SAGINAW, MICHIGAN, ASSIGNOR, BY DIRECT AND MESNE ASSIGNMENTS, TO KLEMM MANUFACTURING COMPANY, OF SAGINAW, MICHIGAN.

STOP MECHANISM FOR TALKING-MACHINES.

1,385,689.

Specification of Letters Patent.

Patented July 26, 1921.

Application filed December 23, 1916. Serial No. 138,636.

To all whom it may concern:

Be it known that I, EDWIN O. KLEMM, a citizen of the United States, residing at Saginaw, in the county of Saginaw and 5 State of Michigan, have invented certain new and useful Improvements in Stop Mechanism for Talking-Machines, of which the following is a specification.

The present invention relates to improvements in sound reproducing or talking machines commercially known as graphophones or phonographs, and in particular to automatic braking mechanism therefor, operable at a predetermined time during the 15 travel of the reproducer or recorder in such manner as to stop the rotation of the usual record support.

The main characteristic features of my invention are the simplicity of its construction, with the resultant elimination of complicated operating parts requiring nicety of adjustment, the adaptability to well known machines at the present time on the market without special construction thereof, and the 25 facility of adjustment of the device whereby it may be caused to effect its braking function when the reproducer has reached a predetermined position with respect to the record with which it coöperates and as 30 may be controlled by the determination of the sound being reproduced or a portion thereof.

It is further comprehended as an object of my invention to provide a device of this 35 character which can be automatically adjusted to automatically stop the machine when the reproducer aforesaid has reached the desired point of the record.

To this end the invention consists of a 40 brake member arranged for coöperation with the record support having an arm for positively actuating the brake member, said arm being automatically adjustable by the reproducer arm to preliminarily set the 45 brake for operation at a predetermined time and sustained in inoperative brake release position by the reproducer arm until such time as the braking action is to be automatically effected through its instrumentality.

50 For a full understanding of the present invention, reference is to be had to the fol-

lowing description and the accompanying drawing in which:

Figure 1 is a fragmentary plan view of a talking machine with my invention applied thereto, parts being broken away and shown in section to disclose the detail features of the device.

Fig. 2 is a fragmentary sectional view showing the brake mechanism in front elevation.

Fig. 3 is an enlarged fragmentary view parts being broken away and shown in section and looking at the brake mechanism from one side thereof.

Fig. 4 is an enlarged sectional view on the line 4—4 of Fig. 1.

Throughout the following detail description and on the several figures of the drawing, similar parts are referred to by like reference characters.

The sound reproducing machine which is of conventional form consists of the casing 1, the rotatable record support 2 mounted upon the usual spindle 3 and operated by the usual motor means not shown in the drawing, and the swinging reproducer arm 4 terminating in the reproducer or sound box 5. The reproducer arm referred to is preferably provided adjacent to its pivot 80 with a forwardly projecting supporting arm 6 secured in any desired manner as most clearly shown in Figs. 1 and 3 of the drawing. The arm 6 obviously rotates with the reproducer arm as the reproducer is moved 85 by the sound groove of the sound record 7 carried by the rotatable support 2 hereinbefore referred to.

The braking mechanism which constitutes the subject matter of this invention consists 90 of the support or bracket 8 which is fixed to the surface of the casing 1 adjacent to the rotatable record support 2 by screws or similar fastening members 9. Rotatably mounted or journaled on this support is a 95 brake member 10 which terminates at its inner end in the brake shoe 11 of any desired material such as is usually provided in braking devices of this character, said brake shoe being adapted to contact with the periphery 100 of the rotatable support when the brake is in applied position. The brake member 10

is shiftable longitudinally in the support 8 when it is rotated by means hereinafter described through the instrumentality of the coaction of a set screw 12 which extends 5 through the support into a spiral groove 13 formed in the surface of said brake member. It will be obvious that rotation of the brake member in one direction will cause said brake member to be shifted longitudinally 10 toward the rotatable support 2 and when rotated in the other direction away from said support releasing the brake by this last mentioned operation. At the end opposite the brake shoe 11, said brake member is 15 apertured to receive the actuating brake arm 14 and against this arm a washer 15 is frictionally held by means of a spring 16 interposed between said washer and the support 8. The spring is of sufficient strength 20 to normally hold the arm 14 at adjusted positions which may be secured automatically at hereinafter described and also exercises sufficient pressure against this arm to prevent movement thereof except when manually actuated to obtain the preliminary adjustment above referred to. As will be noted more particularly by reference to Fig. 4, the arm 14 at one end has connected thereto a blade 17 fixed by means of the connecting 25 members or rivets 18 and the lower edge thereof is provided with a notch or recess 30 which is adapted to receive the supporting arm 6 carried by the reproducer arm 4.

I wish it to be understood that I do not desire to be confined to the particular formation of the end portion of the arm 14 above described as this may readily be changed without departing in any way from the function which is performed by this element, it being, however, desirable that that end of the arm should be of sufficient weight to cause a tendency of the arm to gravitate and in so doing actuate the brake member 10 rotatably upon its support.

45 Describing the operation of this brake mechanism which, it will be obvious, is extremely simple in construction a preliminary adjustment is first obtained which determines the point of application of the brake 50 to the rotatable support 2 as may be desired by the operator. Assuming, for instance, that the brake is to be applied to stop the turntable 2 when the end of the sound groove is reached, the reproducer arm with its supporting arm 6 engaged in the notch 19 of the 55 actuating arm 14 is moved inwardly until the stylus of the reproducer rests substantially at the end portion of the sound groove of the record, thus carrying the arm 14 60 longitudinally therewith. This represents the preliminary adjustment above referred to and the brake will be operated at this point in the subsequent travel of the reproducer arm in the playing of the record. Obviously the operator may make the same ad-

justment so that the brake will be applied when only a portion of the record has been played, in which event the reproducer is preliminarily positioned at the end of that portion of the sound record which is to be reproduced. The operator now presses downwardly upon the free end of the arm 14 rocking the brake member 10 which is withdrawn from contact with the record support 2 by the coaction of the screw 12 and the spiral groove 13 into which it extends. The reproducer arm is now swung outwardly into the dotted line position shown in Fig. 1 where the stylus may be rested upon the initial portion of the sound groove of the record. Releasing pressure on the operating arm 14 the opposite extremity which has been freed from the supporting arm 6 will rest on the surface of said supporting arm in frictional contact therewith. The reproducer arm in the course of the reproduction travels toward the full line position shown in Fig. 1 until the supporting arm 6 arrives at the notch 19 of the operating arm 14 whereupon the latter will gravitate downwardly until said arm is engaged in said notch and in so gravitating the brake member 10 is rotated and caused to shift longitudinally from the release position above described into an impinging relation with respect to the record support 2 thereby stopping the rotation of the latter. It follows from the foregoing that the brake and release actions are obtained by merely a rotation of the brake member 10 while the reproducer arm through its supporting arm 6 acts as a sustaining member normally preventing the rotation of the brake member during the reproduction of the record and it is also apparent that the preliminary adjustment of the brake mechanism is obtained automatically when there is established an interlocking connection between the brake member and the reproducer arm which is manually operated for this purpose, the 100 braking action being finally automatic to stop the record support at the point predetermined by the preliminary adjustment above referred to.

Changes may readily be made in the details of construction of the respective parts of this device without in any way departing from the spirit of the invention and within the scope of the claims hereto appended.

Having thus described my invention, what I claim as new is:

1. In a device of the class described, the combination with a rotatable member and a traveling member movable relative thereto, of brake mechanism arranged to coöperate with the rotatable member to stop rotation thereof, and coöoperating parts between the traveling member and brake mechanism including an actuating member adapted to hold the brake in operative position, said 130

member being adjustable by the traveling member for effecting actuation of the brake sooner or later in the travel of said member.

2. In a device of the class described, the combination with a rotatable member and a traveling member movable relative thereto, of brake mechanism arranged to coöperate with the rotatable member and including an operating member with which the traveling

10 member is adapted to coact to effect brake action at a predetermined time, said operating member normally tending to render the brake mechanism active, a part movable with the traveling member and adapted for ren-

15 dering the brake inoperative until the desired point in the travel of the traveling member is reached, said operating member being preliminarily adjustable incident to movement of the traveling member to determine said desired point.

3. In a device of the class described, the combination with a rotatable member and a traveling member movable relative thereto, of brake mechanism arranged to coöperate

25 with the rotatable member and including an operating member with which the traveling member is adapted to coact to effect brake action at a predetermined time, said operating member being sustained by the traveling

30 member in position rendering the brake inoperative until the desired point in the travel of the traveling member is reached, said operating member being adjustable by movement of the traveling member preliminary to the commencement of its traveling

35 movement.

4. In a device of the class described, the combination with a rotatable member and a traveling member movable relative thereto, of a brake mechanism comprising an actuating member carried by the brake and automatically adjustable by the traveling member, said actuating member being held in inoperative position effecting release of the 45 brake by the traveling member and automatically operable to effect brake action under control of the traveling member.

5. In a device of the class described, the combination with a rotative record support 50 and a traveling member movable relative thereto, of brake mechanism for the record support, and coöoperating means between the traveling member and the brake mechanism to control the latter, comprising relatively 55 movable parts respectively connected to the traveling member and brake mechanism, one of said parts being adjustably carried, and said parts being adapted to interlock at a certain portion of their relative movement, so that a fixed relation of the parts may be 60 had during certain movement of the traveling member for presetting operation in respect to brake operation.

6. In a device of the class described, the 65 combination with a rotatable member and a

traveling member movable relative thereto, of brake mechanism comprising a brake member and operating means therefor coöperative with the traveling member to hold the brake in inoperative position, said means being gravitational to effect braking action of the brake member at a predetermined point in the travel of the traveling member.

7. In a device of the class described, the combination with a rotatable member and a traveling member movable relative thereto, of brake mechanism comprising a brake member, a support in which said member is rotatably mounted, a brake arm arranged to rotate said brake member, and means for shifting the brake member toward or from the rotatable member incident to the rotation of the brake member.

8. In a device of the class described, the combination with a rotatable member and a traveling member movable relative thereto, of brake mechanism comprising a brake member, a support in which said brake member is rotatably mounted, an arm connected to the brake member for rotating the same, means for shifting the brake member longitudinally upon rotation thereof, said arm being manually operable for releasing the brake member, and means coacting with the arm to hold the brake member in such release position until the traveling member has reached a predetermined point in its travel.

9. In a device of the class described, the combination with a rotatable member and a traveling member movable relative thereto, of brake mechanism comprising a brake member, a support in which said brake member is rotatably mounted, an arm connected to the brake member for rotating the same, means for shifting the brake member longitudinally upon rotation thereof, said arm being manually operable for releasing the brake member, and a support carried by said traveling member for holding the brake member in such release position until the traveling member has reached a predetermined point in its travel.

10. In a device of the class described, the combination with a rotatable member and a traveling member movable relative thereto, of brake mechanism comprising a brake member, a support therefor, an arm shiftably carried by said brake member and having a notch therein, a support carried by the traveling member on which said arm rests during the travel thereof, said support being adapted to be received in the notch aforesaid to permit operation of the brake member at a predetermined point in the travel of the traveling member.

11. In a device of the class described, the combination with a rotatable member and a traveling member movable relative thereto, of brake mechanism comprising a brake

member having a notched operating arm, means on said traveling member engageable in the notch to effect relative adjustment of the arm and said means for predetermining 5 the point in the travel of the traveling member for operation of the brake member, said means sustaining the arm and holding the brake in released position during travel of the traveling member until the point 10 aforesaid is reached, said sustaining means being thereupon receivable in the notch to permit the arm to gravitate and effect brake action of the brake member.

12. In a device of the class described, the 15 combination with a rotatable member and a traveling member movable relative thereto, of brake mechanism comprising a brake member, means for shifting said brake member toward or from the rotatable member to 20 effect brake or release actions with respect to the rotatable member, a movable member on which said shifting means is supported during rotation of the rotatable member, said shifting means being constructed 25 to drop automatically at a predetermined time during movement of the movable member to thereby stop the rotation of the rotatable member.

13. In a device of the class described, the 30 combination with a rotatable member and a traveling member movable relative thereto, of brake mechanism comprising a brake member, a support therefor, operating means for said brake member shiftably carried 35 thereby, means mounted on said brake member for holding the operating means at adjusted positions, and means operable with the traveling member and adapted to coact with the operating means to effect adjustment thereof upon manual movement of the 40 traveling member aforesaid.

14. In a device of the class described, the combination with a rotatable member and a traveling member movable relative thereto, of brake mechanism comprising a brake member, a support in which said brake member is journaled for rotation and longitudinal movement, means on said support coacting 45 with the brake member to effect longitudinal movement thereof upon rotation of said brake member, an arm adjustably carried by said brake member for rotating the same, a supporting arm extending from the traveling member on which said brake arm 50 is sustained to normally hold the brake member released during travel of the traveling member, the brake arm being provided with a notch for receiving the supporting arm at a predetermined point in the movement of 55 the traveling member whereby to effect 60 brake action, said brake arm and supporting arm coacting therewith constituting an interlocking connection for obtaining preliminary adjustment of the brake member

through the instrumentality of the traveling 65 member.

15. In a device of the class described, the combination with a rotative record support and a traveling member movable relative thereto, of brake mechanism for the record support, and coöperating means between the traveling member and the brake mechanism to control the latter, comprising relatively 70 movable parts respectively connected to the traveling member and brake mechanism, said 75 parts having two kinds of interaction, one consisting of contact between them such that the brake mechanism is maintained unapplied while the traveling member moves, and the other such that the said contact is discontinued so as to permit application of the brake mechanism to coact with the record support.

16. A device as claimed in claim 15, wherein in the second interaction of the particularly 85 described parts consists of interlocking of said parts so they remain in a relatively fixed relation during adjustment of one of them on movement of the traveling member for the 90 purpose described.

17. A device as claimed in claim 15, wherein the second interaction of the particularly 95 described parts consists of interlocking of said parts automatically at a certain point in the travel of the traveling member, whereby application of the brake mechanism to coact with the record support is effected, and whereby said parts remain relatively fixed while one of them is adjusted 100 relative to and upon manual movement of the traveling member.

18. In a device of the class described, the combination with a rotative record support and a traveling member movable relative thereto, of brake mechanism for the record 105 support, and coöperating means between the traveling member and the brake mechanism to control the latter, comprising a part connected with the brake mechanism, a part connected with the traveling member, said 110 parts being relatively adjustable, and one moving horizontally below and in contact with the second part to keep the brake mechanism inactive, the parts adapted to interlock by relative vertical movement at a predetermined point in their movement in contact 115 with one another so as to permit the brake mechanism to act on the record support and so as to cause the said parts to become relatively fixed, one of said parts being so supported that it is susceptible of adjustment upon manual movement of the traveling member to obtain presetting of the time when the brake mechanism will be permitted to stop the record support.

19. In a device of the class described, the combination with a rotative record support and a traveling member movable relative 120

thereto, of brake mechanism for the record support, and coöperating means between the traveling member and the brake mechanism to control the latter, comprising relatively 5 movable parts respectively connected to the traveling member and brake mechanism, one part being notched at a certain point on its underside, the other arranged to travel horizontally on the unnotched portion of said

first part and then automatically enter the 10 notch to become temporarily fixed relative to the notched part, and one part being adjustable incident to the movement of the traveling member when the fixed relation of the parts is established.

15

In testimony whereof I affix my signature

EDWIN O. KLEMM.
